UNITED STATES PATENT OFFICE

2,551,193

RAIL CAR SAFETY REFLECTOR

David M. Williams, Bushnell, Ill.

Application November 26, 1947, Serial No. 788,104

8 Claims. (Cl. 116—52)

1

This invention appertains to novel and useful improvements in signal devices, particularly those adapted to be utilized in conjunction with rail cars, trucks and the like.

An object of this invention is to swingingly mount an extensible arm having an eccentrically pivoted safety device associated therewith, whereby the safety device will be rotated as influenced by the movement of the swinging arm.

Another purpose of this invention is to provide means for automatically cleaning the safety device.

Another purpose of this invention is to provide means for limiting the travel of the swinging arm and restricting it to pendulous movement.

A still further object of this invention is to provide a base having means for detachably anchoring the same to any suitable support.

Another purpose of this invention is to visually signal from both the front and rear of the safety device.

Another purpose of this invention is to provide an attention-demanding safety device of the visual type which is extremely inexpensive to manufacture, being very simple in structure.

Other objects and features of novelty will become apparent in following the description of the preferred form of the invention, illustrated in the accompanying drawings wherein:

Figure 1 is an elevational front view of the preferred form of the invention, showing a complete cycle of operation in phantom;

Figure 2 is a side view of the invention shown in Figure 1, portions being broken away in section to illustrate details of construction and taken substantially on the line 2—2 of Figure 1 and in the direction of the arrows;

Figure 3 is a plan view of the invention shown in Figure 1;

Figure 4 is a transverse sectional view of the invention in Figure 2 and taken on a line 4—4 thereof and in the direction of the arrows;

Figure 5 is a sectional view taken on the line 5—5 of Figure 2 and in the direction of the arrows, and

Figure 6 is a sectional view of the invention shown in Figure 1 and taken on the line 6—6 thereof and in the direction of the arrows.

Referring now in detail to the illustrated preferred embodiment of the invention, like reference characters are used throughout to indicate similar elements.

This invention has been conceived and developed to provide a device for the purpose of visually signalling a moving vehicle of any particular

2

class, such as railway cars, trucks or other similar devices. Of course, the present invention may be adapted for use in conjunction with boats, ships or the like.

5 It is within the purview of the present invention to utilize the normal rocking, vibrating and shaking associated with vehicles of the class mentioned above for actuation of the signal, safety device.

10 The general operation of the present invention is as follows:

A swingingly supported arm of an extensible nature is provided with bifurcations at one end thereof. Positioned between these bifurcations 15 is a signal device of the visual type, which is eccentrically associated with the said bifurcations. Upon pendulous or swinging movement of the said arm due to the shaking, rocking or other movement of vehicles, the said signal device will be rotated due to its eccentricity.

20 Means for conditioning the said signal device is provided on the said bifurcations. This means consists primarily of a plurality of brushes which are detachably associated with each bifurcation

25 and which engage the faces of the said signal device. As the said device is eccentrically rotated, the brushes will automatically wipe the faces thereof. In certain environments this feature is of material importance such as when the device is utilized in conjunction with railway cars. Here, soot and other undesired substances adhere to the surfaces of the said signal device thereby rendering the same ineffective.

30 The materials of construction which are utilized in conjunction with the present invention are, of course, variable in that this choice resides in sound engineering principles and dictates. However, it is within the purview of the present invention to utilize a type of commercial plastic 35 for use as the signal device which is eccentrically associated with the extensible arm. Luminous material may be utilized in association therewith to further assist in visual signalling.

35 A base 10 is provided of preferably a metallic substance and has means for suitably anchoring the same. This anchoring means may be noted as a pair of split bearings 12 conventionally secured to the base.

40 A support member 14 is secured to the said base 10 by any suitable means such as the screws 16 illustrated in Figure 3. Integrally associated with the said support member 14 is a socket 18 having small cam slots 20 therein.

45 An extensible arm is associated with the said socket 18 and is composed preferably of two ele-

ments 22 and 24, respectively. The said element 22 terminates in a ball 26 which is seated in the said socket 18. The upper portion of the said element 22 is engageable with the said slot 20 for restricting the travel of the said elements 22 and 24 to pendulous, swinging movement.

The said extensible arm is preferably composed of the element 22 which is tubular and the said element 24 which is engageable with the bore of the tubular element 22. A plurality of apertures 28 are provided in the said element 24 and a pair of aligned apertures provided in the said tubular member 22. Any suitable pin or the like may be extended through a selected slot or aperture 28 and through the said apertures in the tube 22. This, of course, retains the elements 22 and 24 in selected, adjusted extensible position.

Bifurcations 30 and 32 respectively, form an extension of the said element 24 and a signal device is journaled therebetween. It is noted that the preferable signal device is composed of a suitable commercial plastic and may be luminous if so desired. Also, eccentric means is utilized for journaling this signal device between the said bifurcations 30 and 32. This eccentric means consists primarily of an aperture positioned off center in the signal device 34, having a pin 36 extending therethrough. This pin, of course, is also journaled in a suitable eye member 38 provided on each of the said bifurcations.

As the extensible arm is pendulously swung, the eccentrically mounted signal device 34 is oscillated about the pivot pin 36 as an axis.

Means for conditioning the outer surfaces of the said signal device 34 is provided. This means is automatically operative upon eccentric, swinging movement of the said signal device 34. The preferential construction is the provision of a plurality of brush elements on the said bifurcations 30 and 32 which contact or engage the outer faces of the said signal device 34. These brush elements may have resilient clips 40 associated therewith which conveniently and efficaciously engage the said bifurcations. This of course renders the said brush elements readily detachable.

While there has been described and illustrated but a preferred form of the present invention it is apparent that variations may be made without departing from the spirit of the invention.

Having thus described the invention, what is claimed as new is:

1. In a safety device, a base, an arm, means for swingingly supporting said arm on said base, a signal device having a signal surface eccentrically pivoted to said arm, and means carried by said arm for cleaning said signal surface during movement of said arm.

2. In a safety device, a base, an arm, means for swingingly supporting said arm on said base, a signal plate eccentrically pivoted to said arm, means for cleaning said signal plate during movement of said arm, and said cleaning means including a brush detachably secured to said arm and contacting said plate to clean said plate when said plate moves with respect to said arm.

3. In a safety device, a base, an arm, means for swingingly supporting said arm on said base, a signal plate eccentrically pivoted to said arm, means for cleaning said signal plate during movement of said arm, said cleaning means including a brush detachably secured to said arm contacting said plate to clean said plate when said plate moves with respect to said arm, and means for securing said base to an anchor means.

4. Means for signaling comprising an extensi-

ble arm, means for swingingly supporting said arm, a signal plate eccentrically pivoted to said arm, means for cleaning said plate when said plate moves with respect to said arm, and said cleaning means being detachably connected with said arm and contacting said plate.

5. Signal means including a base, means for detachably anchoring said base, a socket secured to said base, an extensible arm having a ball, said ball being swingingly mounted in said socket, means for limiting the travel of said arm, a bifurcated extension on said arm, a signal device having a visual signal surface, means for eccentrically mounting said device between the bifurcations of said extensions, a brush detachably secured to the bifurcations and operatively contacting said signal surface and arranged to clean said surface when said plate moves with respect to said brush.

10 6. Signal means including a base, means for detachably anchoring said base, a socket secured to said base, an extensible arm having a ball, said ball swingingly mounted in said socket, means for limiting the travel of said arm, a bifurcated extension on said arm, a signal device having a visual signal surface, means for eccentrically mounting said device between the bifurcations of said extensions, a brush detachably secured to the bifurcations and operatively 15 engaging said signal surface, said limiting means including slots in said socket having portions of said arm engaged therein during the travel of said arm.

20 7. Signal means including a base, means for detachably anchoring said base, a socket secured to said base, an extensible arm having a ball, said ball swingingly mounted in said socket, means for limiting the travel of said arm, a bifurcated extension on said arm, a signal device having visual signal surfaces, means for eccentrically mounting said device between the bifurcations of said extensions, brushes engaging said signal surfaces and detachably secured to the bifurcations, said limiting means including 25 slots in said socket with portions of said arm disposed therein during parts of the travel of said arm, and means for retaining said extensible arm in selected extended positions.

25 8. Signal means including a base, means for detachably anchoring said base, a socket secured to said base, an arm having a ball, said ball swingingly mounted in said socket, means for limiting the travel of said arm, a bifurcated extension on said arm, a signal device having signal surfaces, means for eccentrically mounting said device between the bifurcations of said extensions, brushes engaging said signal surfaces and detachably secured to the bifurcations, said limiting means including slots in said socket with portions of said arm disposed therein during parts of the travel thereof.
